UNITED STATES PATENT OFFICE.

ALFRED D. CARRÉ, OF BRIGHTWOOD, DISTRICT OF COLUMBIA, ASSIGNOR OF ONE-HALF TO CHARLES E. VICKERY, OF KINGWOOD, WEST VIRGINIA.

DESIGN FOR A BICYCLE-SADDLE.

SPECIFICATION forming part of Design No. 25,877, dated August 4, 1896.

Application filed June 1, 1896. Serial No. 593,932. Term of patent 14 years.

To all whom it may concern:

Be it known that I, ALFRED D. CARRÉ, a citizen of the United States, residing at Brightwood, in the District of Columbia, have invented a new and original Design for a Bicycle-Saddle, of which the following is a specification.

This invention relates to a new and original design for bicycle-saddles; and it has for its object to provide a design of this character that shall be both useful and ornamental.

The leading feature of the design resides in a bicycle-saddle having an approximately elliptical body, the true elliptical contour of which is broken at the front edge by a reëntrant V-shaped arch or notch, and the rear edge and ends of which are formed on true elliptical lines, said body being further provided with facial concavities at both sides of its transverse center, a peripheral ridge at the rear edge of the body and tapering in height from the transverse center to the rounded ends thereof, a forwardly-tapering fissure formed in the upper face of the body in line with the transverse center and at its rear edge, a rearwardly-tapering fissure formed in the upper surface of the body and extending rearwardly from the apex of the reëntrant arch or notch, and ridge-elevations at the edges of both of said fissures.

In the drawings, Figure 1 is a perspective view of a bicycle-saddle embodying the herein-described design. Fig. 2 is a plan view thereof. Fig. 3 is a rear edge view of the saddle. Fig. 4 is a cross-sectional view thereof.

Referring to the drawings, the numeral 1 designates a bicycle-saddle body of an approximately elliptical shape. The true elliptical contour or character of the body is broken at its front edge by a reëntrant V-shaped arch or notch 2, but the rear edge and ends of the body are formed on true elliptical lines. The body 1 is provided at both sides of its transverse center with facial concavities 3, and at its rear edge the body is provided with a peripheral ridge 4, which tapers in height from the transverse center to the rounded ends of the body. A forwardly-tapering fissure 5 is formed in the upper surface of the body in line with the transverse center and at the rear edge thereof, and a rearwardly-tapering fissure 6 is formed in the upper surface of the body and extends in a rearward direction from the apex of the arch 2. Ridge-elevations 7 project from the upper surface of the body at the side edges of both of said fissures 5 and 6.

What I claim is—

The design for a bicycle-saddle herein shown and described. 60

In testimony that I claim the foregoing as my own I have hereto affixed my signature in the presence of two witnesses.

ALFRED D. CARRÉ.
